(57) **CLAIM**

The ornamental design for a container, as shown and described.

DESCRIPTION

FIG. 1 is a perspective view of a container in accordance with my new design;

FIG. 2 is a front elevational view thereof, the rear elevational view being a mirror image;

FIG. 3 is a side elevational view thereof, the opposite side elevational view being a mirror image;

FIG. 4 is a top plan view thereof;

FIG. 5 is a sectional view taken along section line 5—5 in FIG. 2;

FIG. 6 is a sectional view taken along section line 6—6 in FIG. 2;

FIG. 7 is a perspective view of the container in accordance with a second embodiment of the invention;

FIG. 8 is a front elevational view thereof, the rear elevational view being a mirror image;

FIG. 9 is a side elevational view thereof, the opposite side elevational view being a mirror image;

FIG. 10 is a top plan view thereof;

FIG. 11 is a sectional view taken along section line 11—11 in FIG. 8; and,

FIG. 12 is a sectional view taken along section line 12—12 in FIG. 8.

The bottom of the container in embodiment 1 and embodiment 2 form no part of the claimed design.

The broken line showing in the drawings is for illustrative purposes only and forms no part of the claimed design.

1 Claim, 3 Drawing Sheets
